HINGE DEVICES

Sven Anders Högedal, Sollebrunn, Sweden, assignor to
Evers & Co. Aktiebolag, a corporation of Sweden

Filed May 15, 1961, Ser. No. 119,005

Claims priority, application Sweden May 19, 1960

7 Claims. (Cl. 16—175)

The present invention relates to hinge devices designed to be used for separable obliquely inclining windows pivotal about a horizontal axis. More particularly, the invention relates to hinge devices of said kind comprising (for each of two opposite sides of the window) a single bearing pivot adapted to be attached to the window sash, said pivot being mounted in a bearing cup adapted to be attached to the adjacent side piece of the window frame, the radial section of said bearing cup on the inside and the outside being confined by such arcs of circles that the pivot is in radial direction movable into and out of said bearing cup.

The invention has for its principal object to provide a hinge device of this kind which will be very efficient and advantageous in use and enable pivoting of the window from closed position to a position in which the outside of the window-pane will be within easy reach for cleansing by a person in the room.

Another object of the invention is to provide a hinge device by means of which the disengagement or removal of the bearing pivot from its bearing cup will be possible only when the window sash has been pivoted from its closed position a predetermined angle.

A further object of the invention is to provide a hinge device of said kind which in the closed position of the window will present no hole through which, for example, cold air could pass from outside when the window is closed.

Still another object of the invention is to provide a hinge device of said kind in which the pivot will present a substantially plane outer surface when mounted in the window sash.

Other objects of the present invention will be made clear by the following description with reference to the accompanying drawings illustrating by way of example a preferred embodiment of the invention.

FIG. 1 is a side elevation of a side piece of a window frame on which the window cup and a stop bar belonging to the hinge device are mounted. FIG. 2 is a side elevation of the corresponding portion of the side piece of the window sash having the bearing pivot mounted thereon. FIGS. 3 and 4 are front views of the parts shown in FIGS. 1 and 2 respectively. FIG. 5 is a front view on a larger scale of the assembled hinge parts. FIG. 6 is a side elevation of the hinge device mounted in a portion of an obliquely inclining window in closed position with the bearing pivot and the guide part being sectioned and the window sash being shown by dot and dashed lines 2' in opened position of the sash. FIG. 7 is a view corresponding to FIG. 6 and showing the window fully opened.

In the drawings, 1 denotes the window frame and 2 the window sash. By means of screws 3 a bearing cup 5 is secured in a recess 4 in the outer side of the frame 1. The outer and inner sides of said cup in radial section being confined by arcs of circles not exceeding about 180 degrees with said cup being preferably substantially semicircular in radial section. Thus, on the side facing from the room said bearing cup is open, and it is also open in the axial direction. The arc-shaped edge of the cup facing to the window sash has a recess 6 extending along a small portion of said edge, and this recess in mounted position of the cup is positioned beneath the horizontal axial center line of the cup.

By means of screws 7 a plate or member 8 is attached

2

to the sash piece 2 and said plate carries a horizontal bearing pivot 9 attached to or formed integrally with the plate. The bearing pivot is substantially semicylindrical corresponding to the bearing cup. Said pivot is preferably formed with a projection 10 the surface 11 of which constitutes an extension of the semicylindrical bearing surface of the pivot. In the normally closed position of the window sash the projection 10 constitutes the upper portion of the pivot. The plate or member 8 also carries a projection or stud 12 rigidly connected to said member and eccentrically positioned at some distance from the bearing surface of the pivot adjacent to the projection 10.

In the closed position of the window sash (FIG. 6) the upper portion of the sash is bearing against stop faces 23 of the frame 1, and from this position the sash is pivotal only in the direction of the arrow. The stud 12 is located at the convex outer side of the bearing cup 5 and the recess 6 is entirely covered by the pivot 9. The plane surface 9a of the substantially semicylindrical bearing pivot 9 will be located in the same plane as the outer surface of the window sash 2 disregarding the small projection 10. This is an advantage in the use of covering sheets or plates for the sash and frame. If the sash be pivoted in the direction shown by the arrow of FIG. 6 the stud 12 in co-operation with the convex side of the bearing cup will serve as a guide member and prevent removal of the pivot from the bearing cup until the window has been rotated a certain predetermined angle as, for example, 130 degrees in which position the stud 12 will register with the recess 6 as shown by FIG. 7 and enable detaching of the window from the frame, if required.

It may be desirable to pivot the window sash through said angle for cleansing of the outer side of the window and it may be also desirable to provide means preventing disconnection of the window after pivoting thereof. For this purpose a stop bar 13 is provided on the frame, said bar being placed in a recess 15 in the side of the frame facing to the sash and slidably in the longitudinal direction of the side piece 1 of the frame. By a reduced end portion 14 this bar extends through an aperture 16 in the bearing cup 5. In axial direction the portion 14 is located at some distance from the outer end surface 9' of the bearing pivot 9 as shown by FIG. 5. A stop pin or stud 17 is attached to the surface 9' adjacent to the projection 10 with said stud projecting axially and being intended to co-operate with the portion 14 of the stop bar 13 when the bearing pivot has been rotated to the position shown by dot and dashed lines in FIG. 6 thus preventing removal of the bearing pivot from the cup 5. In most cases this is desirable when the window is only intended to be pivoted an angle to the cleansing position for the outer side of the window but the window is not intended to be released from the frame. Said angle is only slightly smaller than the pivoting angle required for removal of the window from the frame.

In other cases it may be desirable or prescribed that the window shall be provided so as to enable a quick removal thereof from the frame in urgent situations. Such windows are termed "catastrophe windows." In such cases the stop bar 13 shall not prevent removal of bearing pivot from the bearing cup.

In order to satisfy various demands in this respect, the stop bar 13 is adjustable and provided to be retained in two different positions. For this purpose said bar is provided with a U-shaped recess the base portion 18 of which extends in the longitudinal direction of the bar and the shanks of the U-shaped recess are denoted by 19 and 20 respectively. A pin or screw having a head is fastened to the frame 1 and extends through the recess 18-20. The bar 13 is movable so that said pin selectively may engage with the one or the other shank of the recess. When the pin 21 engages with the shank 19 of

the recess as shown by FIG. 6, the end portion 14 of the bar 13 extends so far into the bearing cup that said portion in co-operation with the stud 17 will prevent rotation of the pivot 9 about an angle large enough to permit the guide part 12 to pass through the recess 6. In the engagement of the pin 21 with the second shank 20 of the recess (FIG. 7) the end portion 14 of the bar 13 has such a position in relation to the stud 17 that the pivot can be rotated a slightly larger angle to permit the guide member 12 to pass through the recess 6 and the disengagement of the pivot 9 from the bearing cup 5. In this latter case the end surface 22 of the bar 13 forms a stop surface which in co-operation with the stud 17 prevents any continued rotation when the bearing pivot 9 moving from the closed position of the window has been rotated an angle in which the guide part 12 is in front of the recess 6 in the edge of the bearing cup.

After opening of the window sash a certain angle the stop bar 13 will be easily accessible by a person in the room for adjustment of the bar from the one to the second position. By means of the screw 21 or a screw for each shank of the recess 18-20, the bar 13 may, if desired be secured in its position.

A hinge device of the kind described and shown is, of course, provided at each of two opposite sides of the window.

By FIG. 3 it is shown that the bearing cup 5 by one end portion 5' extends outside the frame 1. The object of this projecting end portion is to provide a protection against covering sheets on adjacent portions of the roof or wall so that said sheets will not damage covering sheets on the outer side of the window sash if such sheets are used.

The invention is not restricted to a hinge device having in its details the form shown in the drawings but the form of the details may be varied without departing from the spirit of the invention.

What I claim is:

1. A hinge device for one side of a detachable, obliquely inclining window with a sash adapted to be pivoted in a frame about a single horizontal axis, comprising a single bearing pivot adapted to be attached to one of two opposite side pieces of the sash for constituting said bearing axis on one side of the window, said bearing pivot being substantially semicircular in cross-section, an eccentrically positioned stop member on said bearing pivot, a bearing cup for said bearing pivot adapted to be attached to said frame, said bearing cup on the inside and outside being substantially confined by arc-shaped surfaces having said axis as a center-line and permitting disengagement of the bearing pivot from said bearing cup in a direction perpendicular to said axis, said bearing cup having an arc-shaped edge, said bearing pivot extending axially past said edge, a recess in said edge, a guide part adapted to be attached to the sash eccentrically to said bearing pivot in such a relation to said recess that said guide part is normally positioned at the convex surface of said bearing cup and adapted, when registering with said recess, to permit disengagement of said bearing pivot from said bearing cup, a stop bar adapted to be mounted on said frame, said bearing cup having an aperture, one end portion of said stop bar extending through said aperture into said bearing cup, said stop bar located axially outside the outer end surface of said bearing pivot, said stop member and stop bar adapted, in co-operation, to limit the rotation of said bearing pivot to the position in which said guide part is positioned in front of said recess and permits disengagement of said bearing pivot from said bearing cup.

2. A hinge device for one side of a detachable, obliquely inclining window with a sash adapted to be pivoted in a frame about a single horizontal axis, comprising a single bearing pivot adapted to be attached to one of two opposite side pieces of the sash for constituting said bearing axis on one side of the window, said bearing pivot

being substantially semicircular in cross-section, an eccentrically positioned stop member on said bearing pivot, a bearing cup for said bearing pivot adapted to be attached to said frame, said bearing cup on the inside and outside being substantially confined by arc-shaped surfaces having said axis as a center-line and permitting disengagement of said bearing pivot from said bearing cup in a radial direction perpendicular to said axis, said bearing cup having an arc-shaped edge, said bearing pivot extending axially past said edge, a recess in said edge, a guide part adapted to be attached to the sash eccentrically to said bearing pivot in such a relation to said recess that said guide part is normally positioned at the convex surface of said bearing cup and adapted, when registering with said recess, to permit disengagement of said bearing pivot from said bearing cup, a stop bar adapted to be mounted on said frame, said bearing cup having an aperture, one end portion of said stop bar extending through said aperture into said bearing cup, said stop bar being located axially outside the outer end surface of said bearing pivot, said stop member and stop bar adapted, in co-operation, to limit the rotation of said bearing pivot, a substantially U-shaped slot in said stop bar, a pin adapted to be fastened to the window frame and to be received by said slot, said stop bar being adjustable selectively to bring said pin into engagement with one of the shanks of said U-shaped slot whereby said stop bar is either retained in a position in which said stop bar permits disengagement of said bearing pivot from said bearing cup or in a position in which said stop member prevents such disengagement.

3. A hinge device for one side of a detachable, obliquely inclining window with a sash adapted to be pivoted in a frame about a single horizontal axis, comprising a member capable of being attached to one of two opposite side pieces of the sash, a single horizontal bearing pivot extending from said member and constituting the horizontal axis on one side of the window, a single bearing cup adapted to be attached to said frame adjacent to said bearing pivot for reception of the latter, said bearing cup being in substantially semicircular radial section having a concave inner surface and a convex outer surface and adapted to be attached to said frame in a position in which the concave surface of said cup faces substantially outwards from said frame, said cup concave and convex surfaces having said axis as a center-line, said bearing cup in mounted position permitting disengagement of said pivot from the bearing cup in a direction perpendicular to said axis, a substantially semicircular edge of said bearing cup facing said member, said semicircular edge having a recess therein, a guide part provided on said member eccentrically to said bearing pivot in such a position relative to said recess that said guide part in co-operation with the convex surface of said bearing cup prevents disengagement of said bearing pivot in the rotation of said bearing pivot in a direction from a normal position corresponding to the closed position of the window sash through a predetermined angle after which rotation the guide part is in front of said recess and can be moved through said recess into and then out of said single bearing cup.

4. A hinge device as claimed in claim 3 wherein said recess in said normal position is, in its entirety, positioned on a lower lever of said frame than the center line of said bearing cup.

5. A hinge device as claimed in claim 3 wherein said edge recess is, in its entirety, positioned for being on a lower level of said frame than the center line of said bearing cup when mounted and for being covered by said bearing pivot in said normal position of the latter.

6. A hinge device as claimed in claim 3 wherein said bearing pivot in its radial section being substantially semi-circular.

7. A hinge device as claimed in claim 3 wherein said bearing pivot is also substantially semi-circular, the nor-

mally upper portion of said pivot being formed with a relatively small peripherally extending projection having a cylindrical surface forming a direct relatively short continuation of the substantially semi-cylindrical bearing surface of said bearing pivot.
